RADIAL ARM CUTOFF SAW

John E. Kirk and Nina L. Kirk, Kansas City, Mo.

Application September 3, 1946, Serial No. 694,640

5 Claims. (Cl. 143-6)

1

This invention relates to novel and useful improvements to an adjustable saw and more particularly has reference to a cut-off saw which is mounted upon a vertical support shaft and which may be readily adjusted to various positions in the horizontal and vertical planes.

The principal objects of our invention are to provide a rotary saw having a support means which will readily position the saw in a variety of positions; wherein the elevation of the saw may be readily and easily controlled; wherein the radial distance of the saw from its support may be easily regulated; and wherein a tool of great versatility as to use is provided.

These, together with various other objects of our invention which will later become apparent as the following description proceeds, are realized by our device, one embodiment of which has been illustrated by way of example only in the attached drawings, wherein:

Figure 1 is a side elevational view of the device;

Figure 2 is a horizontal sectional view being taken substantially upon the section line 2-2 of Figure 1;

Figure 3 is a side elevational view of the sole support;

Figure 4 is a top plan view of Figure 3;

Figure 5 is a rear elevational view of Figure 1;

Figure 6 is an end view of the supporting means in Figure 1, certain parts being omitted for the sake of clearness; and,

Figure 7 is a perspective view of an element of the support.

Referring now more specifically to the attached drawings, wherein like numerals indicate similar parts throughout the various views, numeral 10 designates the base which may be formed of a generally rectangular plate of any desired size or material, upon which is detachably or if desired integrally mounted an upstanding vertically disposed support standard 12. A generally rectangular carrier plate 14 is adjustably secured upon the standard 12 by means of split clamps 16 and 18 at its upper and lower ends respectively. As will be seen, the carrier 14 may be vertically adjusted or may be swiveled horizontally upon the preferably tubular support or standard 12. A hanger plate 20 is swiveled to the upper portion of the carrier 14 as by a fastening bolt 22, and has its lower portion 24 laterally extended as shown in Figure 6, and has formed therein an arcuate slot 26 struck upon a radius about 22 as a center, through which rides a fastening bolt 28 secured in the lower end of the carrier plate 14, whereby the hanger 24 may be adjusted in various angular

positions upon the vertically disposed carrier plate 14. A pair of spaced guide flanges 30 having in-turned shoulders 32 are removably positioned upon the hanger 20 by means of suitable fastening bolts 34, and serve to guide and retain a generally rectangular slide 36. As shown in Figures 2 and 7 specifically, the slide 36 is formed with laterally extending shoulders 38 adapted for sliding engagement and retention by means of the shoulders 32 upon the guides 30. The back surface of the slide 36 is provided with a longitudinal slot 60 which is adapted to clear the fastening means 22 in the extreme upper position of the slide upon the hanger 20. At its upper end, the slide is formed with a transversely extending arm or bar 40, at the extremities of which are provided apertures or bores 42 and 44 while the body of the slide is provided with an aperture 46 for a purpose to be now set forth.

20 A pair of rods 48 and 50 are adapted for engagement and support in the corresponding bores 42 and 44 respectively, while a third rod 52 is similarly associated with the bore 46. At their outer extremities, the rods 50, 52 and 48 are connected to a frame member 54 which serves to strengthen and reinforce this assembly which constitutes a laterally extending support for a carriage to be set forth hereinafter. The rods 48, 50 and 52 may be formed of any desired cross-section, length or material. Integrally extending from the cross-arm 40 is a lug 56 provided with a bore or aperture 58 for a purpose to be later set forth. The lower surface of the hanger 20, has mounted thereon a bracket 62 provided with a lug 64 whose bore or aperture is aligned with that of the boss 56 and a supporting and operating shaft 66, having a conventional handle 68, is received in the lugs 56 and 64. Rigidly secured to the rod 66, are a pair of spaced collars 70 between which is received the lug 56, said collars constituting a support means for journaling and retaining the shaft or rod 66 upon the hanger 20. The lower portion of the rod 66 is screw threaded as at 72, these screw threads extending through and cooperating with corresponding threads in the aperture of the boss or lug 64. From the foregoing, it will be seen that the laterally extending arms 48, 50 and 52 constitute a frame work carried by the slide 36, and are adjustably mounted upon the hanger 20 by means of the collars 70, lugs 56 and 64. As shown best in Figures 1 and 3, a carriage or platform 74 is hung by means of suitable rollers 76 from the parallel bars 48 and 50, and is provided with a depending bracket or support 78 which journals the shaft 80

of a rotary saw 82 provided with a conventional guard 84. An electric motor 86 is mounted in any convenient manner upon the carriage 74 and is connected as by means of a driving belt 88 with the rotary saw.

From the foregoing, it is believed that the advantages and operation of our device will be now apparent. The carriage 74 and motor 86 and saw 82 may be adjusted in any desired manner upon the radial support arm consisting of the elements 48, 50 and 52. Simultaneously, or alternatively, the radial support arm together with the saw may be adjustable upon the hanger plate 20 by means of the rod 66 and the aforementioned collars and bosses. Additionally, the hanger 20 together with the radial arm supports of the saw and motor, may be swiveled in a vertical plane upon the carrier plate 14 by proper manipulation of the locking bolt 28 in the adjusting slot 26. Finally, the radial arm supports may be adjusted vertically of the standard 12 or horizontally thereabout by means of the split clamps 16 and 18. By means of the foregoing, a power saw has been provided which is extremely flexible as to its positions of adjustment and may be readily assembled or disassembled for storage or portability.

What we claim as our invention is:

1. An adjustable saw comprising a support, a carrier plate vertically mounted on said support, a hanger swivelly mounted on and face to face with said carrier plate, a slide mounted on said hanger for substantially vertical movement, a plurality of laterally extending rods mounted on said slide and constituting a radial support arm, a carriage supported by and longitudinally movable on said rods, a motor and saw mounted on said carriage vertically and swingably horizontally upon said support, said hanger being pivoted to the carrier at one end for swivel movement thereon and means disposed on the other end of the hanger for locking said hanger in selected angular placement.

2. An adjustable saw comprising a support, a carrier plate vertically mounted on said support, a hanger mounted on and face to face with said carrier plate, a slide mounted on said hanger for substantially vertical movement, a plurality of laterally extending rods mounted on said slide and constituting a swivel radial support arm, a carriage supported by and longitudinally movable on said rods, a motor and saw mounted on said carriage, said hanger having laterally spaced guides, said slide being mounted between and retained by said guides, said slide and said hanger having cooperating support lugs and a threaded rod engaging said lugs for adjusting said slide relative to said carrier, an offset section on said hanger, an arcuate slot therein, means disposed in said slot and secured to said carrier for retaining the hanger on selected angular placement around a horizontal axis.

3. An adjustable saw comprising a support, a

carrier plate vertically mounted on said support, a hanger swivelling mounted on and face to face with said carrier plate for selective angular placement thereon, means for locking said hanger in selected position, a pair of extending complementary guide blocks mounted on said hanger, a slide vertically adjustably carried in said guide blocks, cooperating support lugs extending from said slide and hanger, an actuating rod engaging said lugs for vertical positioning of the slide, a plurality of rods extending laterally from said slide, and a carriage supported on said rods, rollers on said carriage for longitudinal movement thereof on the rods, a motor and saw assembly mounted on said carriage.

4. An adjustable saw comprising a support, a carrier plate vertically mounted on said support, a hanger mounted in face to face relation with said carrier plate, a slide mounted on said hanger for substantially vertical movement, a plurality of laterally extending rods mounted on said slide and constituting a radial support arm, a carriage supported by and longitudinally movable on said rods, a motor and saw mounted on said carriage and means for swivelling said hanger and with it said slide rods and carriage about a horizontal axis.

5. An adjustable saw comprising a support, a carrier plate vertically mounted on said support, a hanger superimposed on said carrier plate, a slide mounted on said hanger for substantially vertical movement, a plurality of laterally extending rods mounted on said slide and constituting a radial support arm, means for vertically and angularly adjusting said slide and rods relative to said support and plate, a carriage supported by and longitudinally movable on said rods, a motor and saw mounted on said carriage, said hanger having laterally spaced guides, said slide being mounted between and retained by said guides, said slide and said hanger having cooperating support legs and a threaded rod engaging said lugs for vertically adjusting the side relative to the carrier.
